CLAIM

The ornamental design for an optic, as shown and described.

DESCRIPTION

FIG. 1 is a top front isometric view of the optic.
FIG. 2 is a bottom rear isometric view of the optic of FIG. 1.

FIG. 3 is a top rear isometric view of the optic of FIG. 1.
FIG. 4 is a bottom front isometric view of the optic of FIG. 1.

FIG. 5 is a front elevation view of the optic of FIG. 1.

FIG. 6 is a side elevation view of the optic of FIG. 1.

FIG. 7 is another side elevation view of the optic of FIG. 1.

FIG. 8 is rear elevation view of the optic of FIG. 1.

FIG. 9 is a top plan view of the optic of FIG. 1.

FIG. 10 is a bottom plan view of the optic of FIG. 1; and, FIG. 11 is a cross-sectional view of the optic taken along line 11-11 in FIG. 5.

The evenly dotted broken lines in the drawings illustrate unclaimed features of the optic and form no part of the claimed design.
